UNITED STATES PATENT OFFICE.

FREDERICK J. PETERS, OF MILWAUKEE, WISCONSIN.

SASH-SUPPORTING PLATFORM FOR GLAZIERS.

No. 809,321.

Specification of Letters Patent.

Patented Jan. 9, 1906.

Application filed July 8, 1905. Serial No. 268,077.

To all whom it may concern:

Be it known that I, FREDERICK J. PETERS, a citizen of the United States, residing at Milwaukee, county of Milwaukee, and State of 5 Wisconsin, have invented new and useful Improvements in Sash-Supporting Platforms for Glaziers, of which the following is a specification.

My invention relates to improvements in 10 revolving sash-supporting platforms for glaziers.

The object of my invention is to provide a 15 revoluble platform which may be quickly and readily secured to the top of the table for revolvably supporting a window-sash while the panes of glass are being secured therein.

The construction of my invention is explained by reference to the accompanying drawings, in which—

20 Figure 1 represents a side view of my sash-supporting platform in position for use upon a table of ordinary construction, the supporting-table being shown in vertical section. Fig. 2 represents a top view of my device 25 supported upon a table. Fig. 3 represents a view from the lower side of the sash-supporting platform; and Fig. 4 represents a side view of the sash-supporting platform with parts folded together, so as to occupy less 30 space when not in use.

Like parts are identified by the same reference-figures throughout the several views.

1 represents the central portion of the platform, which is revolvably connected with the 35 top 2 of the table 3 by the bolt 4 and clamping hand-nut 5. To prevent the platform 1 from wabbling upwardly and downwardly or being inclined at an angle to the supporting-table top, I provide the under side of said 40 platform with a plurality of rollers 6, which are connected with the platform 1 by brackets 7 and roller-supporting trunnions 8, whereby the platform is rigidly supported on all sides and is adapted to resist the downward pressure 45 upon the same by the glazier in the act of securing the panes of glass in the sash, while said rollers permit of the platform 1 being freely revolved in one direction, so as to bring all parts of the sash within convenient 50 reach of the glazier as he is doing the work, and the necessity of moving to different sides of the table or of lifting and turning

the sash, as heretofore, when putting the panes of glass in a window-sash is avoided.

It will be understood that when a glazier is 55 in the act of applying putty or other adhesive substance to a window-sash a lateral or side pressure is given to the sash in one direction as the putty is being spread along the marginal edge of the panes of glass. This lateral 60 pressure, it is obvious, will have a tendency to revolve the platform 1 around its central retaining-bolt in the direction that such pressure is applied. To prevent the platform 1 from being thus revolved by the lateral pressure 65 of the operator in the act of spreading the putty, I have provided the table-top 2 with an annular ratchet 9, and I have also provided the platform 1 with a pawl 10, which is pivotally connected at its upper end to the 70 platform 1 by the pivotal bolt 11 and bolt-retaining bracket 12, while the lower end of said pawl is adapted to engage in the teeth of the ratchet 9, and thus prevents the platform 1 from being turned by the lateral pressure 75 of the operator in the act of spreading the putty, as previously described, while the inclination of said pawl to the teeth of the ratchet is such as to permit said platform 1 to be freely revolved in the opposite direction 80 at the will of the operator.

I have shown the platform 1 formed of a plurality of pieces pivotally connected together by hinges 13.

14 is an annular sleeve which is interposed 85 between the platform 1 and the annular ratchet 9 and is retained in place between said parts by the bolt 4. 15 is a hook of ordinary construction which is pivotally connected with one of the folding sides of the platform by 90 the bolt 16 and is adapted when said folding parts of the platform are brought together to engage the opposing bolt 17, whereby said parts of the platform are retained in their folded position.

Having thus described my invention, what I claim as new, and desire to secure by Letters Patent, is—

In a glazier's table, the combination of a 100 stationary table-top; a revoluble platform; means for connecting said revoluble platform at its center with said supporting-table top; a plurality of rollers connected with said revoluble platform and adapted to support the

same from said table-top; an annular ratchet connected with the upper surface of said stationary table-top; a pawl pivotally connected with said platform, said pawl being adapted 5 to move freely over said ratchet as the platform is moved in one direction and to engage said ratchet and lock said platform so as to resist the lateral pressure applied to said plat-

form in the opposite direction, all substantially as and for the purpose specified. 10

In testimony whereof I affix my signature in the presence of two witnesses.

FREDERICK J. PETERS.
